(57) CLAIM

I claim the ornamental design for a swimsuit, as shown and described.

DESCRIPTION

FIG. 1 is a front elevational view of a swimsuit showing my new design;

FIG. 2 is a rear elevational view thereof;

FIG. 3 is a left side elevational view thereof; and,

FIG. 4 is a right side elevational view thereof.

The broken lines in FIGS. 1-4 of the swimsuit are for the purpose of illustrating environment, and form no part of the claimed design.
